(57) **CLAIM**

The ornamental design for a bookshelf, as shown and described.

DESCRIPTION

FIG. 1 is a front, right, top perspective view of the first embodiment of a bookshelf, showing my new design;

FIG. 2 is a rear, left, bottom perspective view thereof;

FIG. 3 is a front, left, top perspective view of its enlarged scale in another angle;

FIG. 4 is a front elevational view of the enlarged scale thereof;

FIG. 5 is a rear elevational view of the enlarged scale thereof;

FIG. 6 is a left side view of the enlarged scale thereof;

FIG. 7 is a right side view of the enlarged scale thereof;

FIG. 8 is a top plan view of the enlarged scale thereof;

FIG. 9 is a bottom plan view of the enlarged scale thereof;

FIG. 10 is an enlarged view of detail 10 in FIG. 3;

FIG. 11 is an enlarged view of detail 11 in FIG. 3;

FIG. 12 is a front, right, top perspective view of the second embodiment of a bookshelf, showing my new design;

FIG. 13 is a rear, left, bottom perspective view thereof;

FIG. 14 is a front, left, top perspective view of its enlarged scale in another angle;

FIG. 15 is a front elevational view of the enlarged scale thereof;

FIG. 16 is a rear elevational view of the enlarged scale thereof;

FIG. 17 is a left side view of the enlarged scale thereof;

FIG. 18 is a right side view of the enlarged scale thereof;

FIG. 19 is a top plan view of the enlarged scale thereof;

FIG. 20 is a bottom plan view of the enlarged scale thereof;

FIG. 21 is an enlarged view of detail 21 in FIG. 14; and,

FIG. 22 is an enlarged view of detail 22 in FIG. 14.

The dashed broken lines in the figures are for the purposes of illustrating portions of the bookshelf and form no part of the claimed design.

(Continued)

The short-short-long dashed broken lines immediately adjacent to the claimed areas in the views represent the boundaries of the design and form no part of the claimed design. The dash-dot-dash broken lines are for notating enlarged views and form no part of the claimed design.

1 Claim, 22 Drawing Sheets
